Primary Examiner — Amber R Stiles*Assistant Examiner* — Lilybeth M Mcallen*(74) Attorney, Agent, or Firm* — ScienBiziP, P.C.(57) **CLAIM**

The ornamental design for a bottle, as shown and described.

DESCRIPTION

FIG. 1 is a perspective view of a bottle showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof; and,

FIG. 9 is a view of a bottle in use, with the bottle mouth fixed by the drainage cap.

The broken lines in the drawings illustrate the portions of the bottle, which form no part of the claimed design.
